DESIGN FOR A MOLD FOR AN ICE CREAM CONFECTION

Benedict E. Heggy and Herman G. Smith, Canton,
and Ray J. Schott, Louisville, Ohio

Application June 20, 1935, Serial No. 57,356

Term of patent 14 years

To all whom it may concern:

Be it known that we, Benedict E. Heggy, Herman G. Smith, and Ray J. Schott, all citizens of the United States, residing, respectively, at Canton, Canton, and Louisville, in the county of Stark and State of Ohio, have invented a new, original, and ornamental Design for a Mold for an Ice Cream Confection, of which the following is a specification, reference being had to the accompanying drawing, forming part thereof.

In the drawing:

Figure 1 is a plan view of a mold for an ice cream confection in open position, showing our new design;

Fig. 2 is a side elevational view of the mold for an ice cream confection in closed position, and

Fig. 3 is an end view of the mold for an ice cream confection in closed position.

We claim:

The ornamental design for a mold for an ice cream confection, as shown and described.
